UNITED STATES PATENT OFFICE.

WALTER STUMPF, OF BALTIMORE COUNTY, MARYLAND, ASSIGNOR TO THE BLACK & DECKER MANUFACTURING COMPANY, OF TOWSON, MARYLAND, A CORPORATION OF MARYLAND.

PORTABLE POWER-DRIVEN RIVET SPINNING AND PRESSING TOOL.

Application filed October 15, 1925. Serial No. 62,637.

The invention relates to manually portable power-driven rotary tools and particularly to such a tool for use in heading rivets by spinning. The rivets are in accordance with the 5 present practice in rivet spinning ordinarily driven cold, though the tool may be applied to hot riveting.

The tool as shown in the present application is provided with an electric motor connected by suitable gearing to a rotary spindle which is equipped with a spinning tool adapted to engage the point of the rivet and when rotated at the desired speed and applied with a suitable degree of pressure to so displace 10 the metal as to upset the rivet point, expanding it laterally and forming a smooth convex head. An important feature of the invention is the provision in a tool of the general type described, i. e., a manually portable 15 power-driven rotary tool, of means for applying a spinning tool to the rivet or similar member to be upset as described, with necessary pressure to displace the metal and upset or head over the point of the rivets.

20 The means referred to consist of a rivet head supporting member, referred to herein as an anvil, and means for forcing the anvil toward the spinning tool and vice versa, compressing the rivet between the anvil and spinning tool, the rivet being ordinarily supported laterally by the walls of the hole through which it is passed in the material being riveted.

25 The tool, as shown, is particularly adapted for use with large work, as the manufacture of automobile bodies and the like, which cannot be easily moved to be engaged by the operative elements of stationary machines, and it may be used to advantage in stationary 30 structures and in numerous instances with small work as brake lining and the like.

In the form shown the anvil is mounted on a transverse arm or foot of an L-shaped sliding bar which slides in bearings in the frame or case of the tool, the motion being parallel to the spindle. The sliding bar is controlled and forced toward the spinning tool by means of a slow motion pressure multiplying gear shown in the form of a toggle joint controlled 35 by an elongated hand lever.

In the preferred form shown, one link of the toggle is formed by the end of the lever, the toggle link being substantially at right angles to the length of the actuating lever,

In the accompanying drawing I have illustrated a rivet heading or spinning machine embodying my invention in what is at present regarded as the preferred form.

In the drawings—

Figure 1 is an elevation of the tool on a small scale.

Figure 2 is a section on the spindle axis taken through the lower end of the tool casing on line 2—2 Figure 4, showing the spindle with the spinning tool, anvil and anvil support and actuating means in elevation. 65

Figure 3 is a view looking from the right in Figure 2, showing fragmentarily the sliding bar and actuating means, the plane of the figure intersecting the actuating lever on line 3—3. 70

Figure 4 is a section on the line 4—4 of Figure 2 looking upward, showing the spindle and other parts of the tool except the anvil in bottom plan. 75

Referring to the drawings by numerals, each of which is used to indicate the same or similar parts in the different figures, the machine as shown includes a motor 1, which is preferable an electric motor, a spindle 2 mounted in an elongated bearing 3 in the tool casing 4, and carrying at its lower end a rivet spinning tool 5. The spindle 3 is driven from the motor 1 by a train of reducing gears comprising a pinion 8 formed on 80 the shaft 6 of the motor, which meshes with a gear 7 mounted on the frame on a suitable stud, not shown, and carrying a pinion 9 which meshes with a toothed gear 10 on the spindle. The motor is provided with suitable shaft bearings 11, as shown, and the spindle 2, in addition to being mounted in an elongated bearing 3, is provided with a thrust bearing 12 in a recess 14 in the frame engaging a suitable flange 15 on the spindle. 85

It is of particular interest, in the preferred construction shown, that the tool casing is provided with a rigid integral extension 16 which supports the bearing 3 which extends almost the entire length of the spindle, the exception being the portion occupied by the flange 15 and spinning tool carrier 17. The casing or frame extension also provides a support for the anvil to be described. 100

The anvil 20 supported in the rigid extension 16, as aforesaid, which carries the spindle, is mounted on a sliding bar 21 which may be referred to as L-shaped in that it has 105

a transverse foot 22 which carries the anvil at one end directly beneath the spinning tool 5. The sliding bar 21, as shown, is of rectangular cross-section, though the shape is 5 not of particular importance, the rectangle being elongated in the direction of the radius of the spindle and is mounted to slide in a bearing slot 23 in the frame, the slot and the direction of motion being parallel to the 10 spindle 2. The slot as shown is open at the end at 24 from which the sliding rod protrudes and for its entire length on the side remote from the spindle, being closed as to this side by a cover plate 25 which is conveniently removable and is held by screws 26 or in any suitable manner. The sliding bar and anvil are actuated by means of a suitable slow motion pressure multiplying mechanism shown in the form of a toggle mechanism 20 operated by hand lever 31, the anvil being moved down to admit the work between the anvil and the spinning tool and moved toward the spinning tool to press the spinning tool against the rivet or more properly to compress the rivet in the direction of its length between the anvil and spinning tool. The toggle, as shown, is composed of a link 32 pivotally mounted on the machine frame by means of a suitable stud 33 seated 30 therein and pivotally connected at its upper end at 34 to the laterally expanded end 35 of the lever 31, which acts as the second link of the toggle, being pivotally connected at 36 to the sliding bar 21 by means of a suitable stud seated in the bar. The end 35 of the lever 31 is as will be noted by examination of Figure 3, mounted in a slot 37 shown also in dotted lines in Figure 2, which provides an opening through the tool casing, exposing a 40 portion of the sliding bar 21 in which the stud 36 is seated, the bar and anvil being shown in Figure 2 at the upper or rivet pressing position. The tool may be referred to in accurate descriptive terms as a portable power-driven rivet spinning and pressing tool.

The operation will be easily understood from the preamble and description. The handle 31 is first raised to lower the anvil or 50 more properly to space it away from the spinner, and the rivet having been inserted, the work is passed between the anvil and spinner, the head of the rivet being engaged with the anvil, being conveniently centered by 55 means of the depression 38 therein. The handle 31 is then forced down, bringing the rivet pins 33, 34, 36 of the toggle lever into alignment and forcing the upper pin 36, Figure 2, which is seated in the sliding bar 21, 60 carrying the anvil upward to its uppermost position, in which position the anvil and the spinner are caused to approach, placing the rivet under longitudinal compression, forcing the spinning tool against the point of the 65 rivet. The motor having been started pref-

erably prior to the final application of pressure, the spinning tool is rotated at a relatively high speed, the friction thus applied by the pressure and high speed of rotation of the spinning tool serves to gradually displace 70 the metal of the rivet laterally, forming a head or upsetting the rivet in a shape in conformity to the shape of the spinning tool, which as shown consists of a pair of rollers 39, presenting as combined a laterally concave peripheral face 42, the rollers being mounted to rotate on a pin 40 in forks 41 of the spinner tool shank 17.

The tool, as shown, has important advantages in its application to large work where 80 a manually portable tool may be moved to convenient positions to conform to the shape of the work which cannot itself be as conveniently moved for the purpose of working with a stationary tool, and the tool may be 85 used on stationary work.

The construction described has notable advantages, particularly in the extension 16 of the frame, which provides an elongated bearing and a thrust bearing for the spindle, and 90 a slide bearing integral therewith for the sliding bar 21 carrying the anvil, giving absolute rigidity of the parts in applying pressure to the rivets, and in the compact arrangement whereby the anvil is actuated by 95 the hand lever 31, applying sufficient pressure to the rivet by slight pressure on the hand lever, the entire mechanism being convenient, compact and powerful and capable of operation by unskilled labor, giving the 100 highest degree of efficiency in the way of speed and perfection of the work produced.

I have thus described specifically and in detail a single embodiment of my invention in order that the nature and operation of 105 the same may be clearly understood; however, the specific terms herein are used descriptively rather than in a limiting sense, the scope of the invention being defined in the claims.

What I claim and desire to secure by Letters Patent is:

1. A manually portable power-driven tool having a motor, a frame supporting the motor and having an integral extension, a 115 spindle mounted in the extension and having an elongated bearing therein with gearing connecting the motor to the spindle, a bearing in the extension parallel to the spindle, a sliding bar mounted therein, means for supporting a spinning tool on the spindle, an anvil mounted on the sliding bar in alignment with the spindle, and means for moving the sliding bar with a slow, pressure-multiplying motion to compress a rivet between the anvil and spinning mechanism.

2. A manually portable power-driven tool having a motor, a casing enclosing the motor and having an integral extension, a spindle mounted in the extension and having 130

an elongated bearing therein with gearing connecting the motor to the spindle, a bearing in the extension parallel to the spindle, a sliding bar mounted therein, means for supporting a spinning tool on the spindle, an anvil mounted on the sliding bar in alignment with the spindle, and means for moving the sliding bar with a slow, pressure-multiplying motion to compress a rivet between the anvil and spinning mechanism, said means comprising a toggle mechanism and a hand lever actuating the same.

3. A manually portable power-driven tool having a motor, a frame carrying the motor and having an integral extension, a spindle mounted in the extension and having an elongated bearing therein with gearing connecting the motor to the spindle, a sliding bar having a bearing in the extension parallel to the spindle, means for supporting a spinning tool on the spindle, an anvil mounted on the sliding bar, in alignment with the spindle, and means for moving the sliding bar with a slow, pressure-multiplying motion to compress a rivet between the anvil and spinning mechanism, said means comprising

a toggle lever composed of two links, a hand lever formed integral with one link, a pivot pin connecting the hand lever to the sliding bar at the upper end of the toggle, a pin connecting the hand lever to the lower link, and a pin connecting the lower end of the lower link to the frame.

4. In a manually portable tool, a motor, a frame carrying the motor and having an integral extension, a spindle having an elongated bearing in the extension, and driving connections to the motor, means connecting a rivet spinning tool to the spindle, an anvil, a sliding bar supporting the anvil, a slide bearing for the bar in the extension parallel to the spindle, the bearing being open at one side, a removable cover therefor, a hand lever for actuating the sliding bar to compress a rivet between the spinning tool and anvil, and slow motion, pressure-multiplying means controlled by the handle to actuate the sliding bar.

Signed by me at Baltimore, Maryland, this 13th day of October, 1925.

WALTER STUMPF.
